UNITED STATES PATENT OFFICE.

HENRY F. HOFFMAN, OF NEW YORK, N. Y.

RECIPROCATING PUMP.

1,248,118.

Specification of Letters Patent. Patented Nov. 27, 1917.

Application filed October 26, 1916. Serial No. 127,766.

To all whom it may concern:

Be it known that I, HENRY F. HOFFMAN, a citizen of the United States, and a resident of the city of New York, Stapleton, 5 borough of Richmond, in the county of Richmond and State of New York, have invented a new and Improved Reciprocating Pump, of which the following is a full, clear, and exact description.

10 This invention relates to reciprocating pumps or the like and has particular reference to such machines adapted particularly, though not necessarily, to ammonia compressors or the like.

15 Among the objects of the invention is to provide piston and delivery valve mechanisms so designed that the fluid being pumped will be permitted to pass as freely as possible from one stage to the next, where- 20 by friction and consequent heating of the parts will be reduced to a minimum.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had 30 to the accompanying drawings, in which like reference characters designate the same parts in the several views, and in which—

Figure 1 is a vertical sectional view of a preferred embodiment of the invention;

35 Fig. 2 is a side elevation of the discharge valve, one of the valve plates being indicated in dotted lines in open position;

Fig. 3 is a side elevation of the piston partly in section on the line 3—3 of Fig. 4;

40 Figs. 4 and 5 are horizontal sections on the lines 4—4 and 5—5 respectively of Fig. 1;

Fig. 6 is a vertical sectional detail through the piston on the line 6—6 of Fig. 4;

45 Fig. 7 is an edge view of one of the piston valves; and

Fig. 8 is a transverse sectional detail of the discharge valve stem on the line 8—8 of Fig. 2.

50 Referring now more particularly to the drawings, I show a cylinder 10 having a head 11 at one end with a stuffing box 12 through which the piston rod 13 reciprocates. Adjacent this head 11 is the in- 55 take 14.

The piston is shown as a whole at 15 se-

cured to the end of the rod 13 in any suitable manner.

Secured to the upper end of the cylinder is a delivery head 16 with an outlet neck 17.

60 The discharge valve above referred to is indicated as a whole at 18 and comprises a disk 19 having a finished rim or surface at 20 bearing normally upon a finished upper edge or rim 21 of the cylinder. At the center of the disk is secured a stem 22 which leads upwardly through a stuffing box 23 constituting a part of the delivery head 16 and including a detachable cap 24 formed with a hole 24' adapted to receive a pet cock 70 or the like (not shown). This pet cock is designed normally to be kept closed, but is adapted to be opened to permit the escape of fluid under high pressure in the delivery head, the escape being provided for by 75 means of a series of longitudinal grooves 25, extending along the stem 22. The length of these grooves is such that they extend beyond the upper and lower surfaces of the inner or base portion of the stuffing box 23. 80 A heavy coil spring 26 surrounds the stem 22 and bears at one end upon the top of the disk holding it normally seated, while the other end of the spring bears against said base of the stuffing box. The upper end 27 85 of the stem is formed polygonal for the application of a T-wrench or the like, whereby the valve may be rotated for the purpose of redressing the surfaces 20 and 21 when the cap 24 is removed.

90 I will now describe more particularly the construction of the piston 15 and the valve plates. The piston is provided at its center with a hub 28 and at its periphery with a cylindrical shell 29 in which are fitted a series of packing rings 30 of any suitable construction for direct co-operation with the inner surface of the cylinder. The hub and shell are connected by a series of radial webs 31, shown as four in number extending 95 throughout the full vertical length of the piston, giving thereby ample strength for the structure, but at the same time insuring maximum open space vertically through the piston. The upper ends of the hub 28 and the shell 29 are arranged in the same plane and form, together with the side edges 31' of the webs 31, a plurality of finished seats for a like number of pivoted valve plates, each of which is adapted to oscillate from 100 horizontal position upwardly to an inclined position, such as indicated in Fig. 3, around 110

a horizontal pivot 33 arranged radially with respect to the piston rod and extending through overlapping ears 32' of a plate 32 and through ears 34 secured to the upper 5 edge of the adjacent web 31. The structure surrounding each of the valve plates is rabbed at its periphery, as shown at 35, providing thereby a more reliable seating of the valve plate and facilitating the dressing or 10 grinding operation for maintaining the same in good condition. As will be noted particularly from Fig. 7, each valve plate is provided with a stop lug 36 on the opposite side of the pivot pin 33 from the main portion 15 of the plate. This lug enters a groove or channel at 35 and limits the upward swinging movement of the plate. The periphery of each valve plate likewise is finished for coöperation with the valve seat 20 above referred to. It will be appreciated that a series of four valve plates arranged as indicated, all opening upwardly freely as far as necessary insure free passage of the fluid upwardly through the piston be- 25 tween the several pairs of webs 31, and since the valve plates are held or limited in their movement to inclined position, they are quick to respond to the closing action. Furthermore, since there are so many of these 30 valve plates and of large capacity, the actual extent of opening movement is comparatively slight. Thereby the quick and effective closing or seating of the valve plates is assured.

35 The discharge valve with respect to a series of valve plates 37 is essentially the same as the structure of the piston with respect to its valve plates 32, that is to say, the disk 19 comprises a series of radial ribs 38, each

having a plurality of ears 39. Between the 40 ribs are provided openings normally closed or guarded by the plates 37, each of which has ears 40 pivoted to the adjacent ears 39 by means of radial pins 41, but the active surfaces of the plates and the valve plate 45 seats are formed substantially the same as described above in connection with the piston, and the opening movement of the plates 37 is limited by lugs 42 on the opposite sides of the pivot pins. 50

According to the design of this pump, it is possible and expedient in the manipulation of single acting pumps, for ammonia compressors for example, to operate the machine at a high degree of efficiency without 55 any danger of overheating the machine or the gas. The device is of simple construction and its up-keep is amply provided for in a cheap and reliable manner. 60

I claim:

In a reciprocating pump, the combination with a cylinder having inlet and outlet openings and a piston reciprocating between said openings, of closure means for the outlet opening comprising a disk having a series 65 of openings therethrough in the same plane, a plurality of valve plates swinging upwardly from but normally closing said openings, a central stem extending from the disk and perpendicular thereto, guide means for 70 the stem, said stem being provided with longitudinal grooves extending through the guide means and having a polygonal upper end, and a spring interposed between the disk and said guide means normally holding 75 the disk seated.

HENRY F. HOFFMAN.
